COSMETICS ORGANIZER TRAY

Lois A. Huncovsky, 4897 Hidalgo,
San Diego, Calif. 92117

Filed Nov. 23, 1966, Ser. No. 4,783

Term of patent 14 years

(Cl. D86—10)

I claim:

The ornamental design for a cosmetics organizer tray, substantially as shown and described.
